US0D1087019S

(12) **United States Design Patent** (10) Patent No.: **US D1,087,019 S**
(45) Date of Patent: ** Aug. 5, 2025

(54) **CHARGING STATION FOR ELECTRIC VEHICLES**

(71) Applicant: **Ads-tec Energy GmbH**, Nürtingen (DE)

(72) Inventor: **Thomas Speidel**, Nürtingen (DE)

(**) Term: **15 Years**

(21) Appl. No.: **35/516,980**

(22) Filed: **Dec. 23, 2022**

(80) **Hague Agreement Data**

Int. Filing Date: **Dec. 23, 2022**

Int. Reg. No.: **DM/228208**

Int. Reg. Date: **Dec. 23, 2022**

Int. Reg. Pub. Date: **Apr. 28, 2023**

2.1 : Front

2.2 : Back

2.3 : Left

2.4 : Right

2.5 : Perspective

2.6 : Perspective

2.7 : Perspective

The broken lines in the reproductions illustrate portions of the article that form no part of the claimed design. The ray lines, shown in the reproductions of the second embodiment, represent illumination of the elements shown with an oblique parallel line pattern. The bottom view of each of the embodiments is omitted and forms no part of the claimed design.

1 Claim, 14 Drawing Sheets
